UNITED STATES PATENT OFFICE.

GEORGE E. THIMMES, OF MECHANICSVILLE, IOWA.

AUTO SIGNAL DEVICE.

Application filed October 14, 1924. Serial No. 743,529.

To all whom it may concern:

Be it known that GEORGE E. THIMMES, a citizen of the United States, residing at Mechanicsville, in the county of Cedar and 5 State of Iowa, has invented certain new and useful Improvements in Auto Signal Devices, of which the following is a specification.

The present invention relates to direction 10 indicating signals more particularly adapted for use on a vehicle.

An object of the invention is to provide a direction signal which has a plurality of selectively operable indicator arms embodying 15 a casing for normally housing and protecting the arms and a novel guide member carried by the casing in a peculiar manner, so that the parts may be easily assembled and the guide member may be swung into 20 open and closed positions for gaining access to the interior of the casing for assembling the parts, making adjustments and repairs and replacements.

Another object of the invention is to provide 25 a device of this character which embodies relatively few parts capable of being economically stamped and which presents a rigid and durable structure.

A further object of the invention is to provide 30 an improved operating device which may be located in spaced relation to the signal casing and in position of easy access to the operator of the vehicle.

A still further object of the invention is to provide 35 a signal casing which is capable of being supported along one of the uprights of the wind shield of a vehicle in position, so as not to interfere to any practical extent with the line of vision and at the same time 40 to support the signal arms in such manner that they may be easily and readily observed when brought into signal position.

With the foregoing and other objects in view, the invention will be more fully described hereinafter, and will be more particularly pointed out in the claims appended hereto.

In the drawings, wherein like symbols refer 50 to like or corresponding parts throughout the several views,

Figure 1 is a side elevation of a portion of a motor vehicle having a signal device constructed according to this invention applied thereto.

Figure 2 is a vertical section taken 55 through the same substantially on the line 2-2 of Figure 1, and showing the interior construction of the signal box and its parts.

Figure 3 is an enlarged horizontal section taken through the upper end of the signal 60 box substantially on the line 3-3 of Figure 2.

Figure 4 is a similar view taken through the lower end portion of the signal box or casing substantially on the line 4-4 of 65 Figure 2.

Figure 5 is a fragmentary vertical section taken through the upper projecting portion of the signal casing substantially on the line 5-5 of Figure 2. 70

Figure 6 is an enlarged longitudinal section taken through the operating device for selectively actuating the signal arms, and

Figure 7 is a transverse section taken through the intermediate portion thereof 75 substantially on the line 7-7 of Figure 6.

Referring to the drawings, 10 designates the body of a motor vehicle or the like to which the signal device is adapted to be applied. The vehicle 10 is shown as being an 80 instrument board 11 of the usual type and provided with a cowl 12 extending forwardly from the wind shield 13.

The signal device includes a box or casing 14 which is adapted to be disposed vertically against the forward side of the wind shield 13 and at the edge thereof, such as at the left edge in front of the operator of the vehicle. The housing 14 is provided with a preferably solid rear wall and solid 85 lateral walls forming the casing, and the lateral walls have at their upper ends outstanding parallel wings 15 which are coextensive with the upper edges of the side walls of the casing 14 and adapted to support a cover 16 which is hinged at 17 to the upper edge of the rear wall of the casing. The wings 15 preferably have stepped outer edges and the cover 16 is provided with a correspondingly shaped depending 90 flange 18 arranged to extend across the wings and may have inturned edges for overlapping the same. The lower step of the flange 18 is provided with a pair of vertically 95 slideable bolts or pins 19 upon the lower ends of which is mounted a transverse buffer 20 comprising a suitable frame with a strip of felt 21 or other suitable shock

absorbing material across its lower edge. The cover 16 may also be provided with a lamp housing 22 projecting upwardly and outwardly with the open side of the housing 5 directed downwardly in position to reflect rays from a lamp 23 onto signal arms or devices when projected from the housing 14.

As shown in Figure 5 the cover 16 may be locked in closed position by pins 24 carried upon the upper ends of leaf springs 25 fixed at their lower ends against the inner opposite sides of the wings 15 and which normally urge the pins 24 outwardly through registering openings formed in the wings 15 and in the depending lateral flanges of the cover 16. The springs 25 may be pressed inwardly by finger pins 26 carried upon the springs 25 and extending outwardly through and beyond the wings 15 20 for receiving pressure from the fingers or the like.

The casing 14 is provided with a plurality of indicating arms 27 mounted to independently turn upon a transverse tube 28 extending between the sides of the casing 14 in the upper end thereof and near its outer edge. A rod 29 passes through the tube 28 and is secured in the side walls of the casing for supporting the tube, and the tube 28 has spacing washers 30 thereabouts between the arms 27 to maintain the same in properly spaced relation in the casing. The arms 27 are normally held in suspended position and within the casing 14 each by a helical spring 31 secured at one end to its arms 27 and at its other end to the top of a combined guard and spacing member later described and carried in the housing 14.

The lower end of the spring 31 is attached to its arm 27 by a hook 32 the bill of which is directed outwardly and upwardly, so that the spring may be easily detached from the arm 27 when desired.

The combined guard and spacing member 45 is preferably formed from a single length of metal suitably cut to provide spaced vertical bars 33 having slots therebetween of a size to permit the free operation of the arms 27, the plate or sheet providing the bars 33 50 being offset inwardly at the lower end of a casing by a hinge lip 34 which is hinged at 35 to the outer edge and lower end of the casing 14 as shown in Figure 2. The bars 33 incline upwardly and outwardly 55 when in normal position, so as to at all times engage the opposite sides of the intermediate signalling arms 27 and thus maintain the same against undue vibration or binding in the casing. The bars 33 are each 60 reinforced by inturned flanges or edges 36 forming flat bearing surfaces to engage the sides of the arms 27.

The upper ends of the bars 33 are connected together by a horizontal cross piece

37 integral with the bar structure and which is adapted to seat against the under side of the cover 16 when the latter is closed and which is relatively narrow and provided with an inclined guard 38 at its rear edge. The guard 38 is similarly constructed to the front plate structure forming the bars 33 and is inclined downwardly and toward the back wall of the casing and has a lower edge portion adapted to project beneath a clip 39 secured to the rear wall of the casing 70 75 14. The guard member 38 is relatively short and is adapted to receive in the slots thereof the heels or inner ends of the signal arms 27 and thus steady the same at the upper end of the casing. The slots in the guard member 38 correspond in number and position to the slots between the bars 33, so as to engage the opposite sides of the signal arms at their upper ends at all times.

The signal arms 27 are each provided with a bail 40 pivoted at 41 to its respective arms 27 at a point above and slightly to the rear of the tube 28. The bails 40 extend downwardly beneath the guard 38 and normally lie at the rear edges of the arms 27 90 and have springs 41 attached thereto which in turn are connected to wires or cables 42 which extend downwardly through the open bottom of the casing 14.

The casing 14 may be supported upon a special bracket 43 of triangular cross section as shown in Figure 2 with a plate 44 having upturned flanges 45 adapted to engage upwardly within the bottom of the casing 14, the plate 44 having at its inner edge 100 an attaching flange 46 adapted to be secured to the cowl 12 of the vehicle in any suitable manner. The lower end of the bracket 43 is provided with an attaching flange or portion 47 adapted to lie flat against the cowl 105 12 and be secured thereto in any suitable manner.

The plate 44 is thus supported in a substantially horizontal position to maintain the casing 14 in upright position. The casing is further secured in place by a bolt 48 which passes through the inner side of the casing 14 and through the adjacent frame part of the wind shield 13 as shown to advantage in Figure 1.

The plate 44 terminates in spaced relation to the inner end of the bracket and provides an opening through which the wires or cables 42 may freely pass, and the cowl 12 is also provided with an opening 49, so that the cables 42 may be carried within the cowl. The lower end of the casing is provided with rollers 50 over which the cables 42 may pass to maintain the cables in spaced apart positions, and the cowl 12 is provided upon its inner side and at one side of the opening 49 with a roller 51 to receive the cables 42 thereover, the cables 51 being car-

ried over another roller 52 on the inner side of the instrument board 11, the cables extending inwardly through the latter.

- For the purpose of selectively operating 5 the cables 42 and their respective signals arms 27, an operating member is employed such as shown in Figures 1, 6 and 7. This operating member has a casing 53 secured to the upper side of the instrument board 10 11 and suitably apertured at its lower end to receive the cables 42 therethrough. The partition 54 is secured across the interior of the casing 53 near its upper end and forms a guide for a plurality of pull rods 15 55 which extends through the partition 54 and through the top of the casing 53. The pull rods 55 have rings 56 upon their upper ends to facilitate grasping of the same by the fingers and the rods 55 are normally 20 urged downwardly by springs 57 which surround the rods and are disposed between the partition 54 and adjustable collars 58 arranged upon the lower end portions of the rod. The rods have notches 59 in their 25 edges adapted to interlock with the top of the casing 53 when the rods are pulled out to the desired extent for holding the rods in such position until it is desired to release the same.
- 30 The lower ends of the rods 55 are provided with inwardly extending arms 60 which overhang the opening through the lower end of the casing 53 and for direct attachment to the cables 42, so as to 35 draw the same directly over the roller 52 on the instrument board 11.

In operation it is only necessary to draw the selected rod 52 upwardly through its casing 53 and lock the rod in such position 40 by the notches 59. When the rod 55 is drawn upwardly the corresponding cable 42 is drawn over the rollers 52, 51 and 50 and the corresponding bail 40 is drawn downwardly in the housing 14.

45 This action swings the respective signal arm 27 outwardly through the guard and spacing member into a horizontal position and jar is absorbed through the felt 21. The spring 41 may extend under abnormal 50 pressure so as to prevent injury to the parts. The signal arms may be provided with any suitable indicating indicia such as is shown in Figure 2 where the adjacent arm 27 has an arrow 61 pointing toward the free end 55 of the arm and the latter also has the letter L as shown at 62 to indicate left, or the direction shown by the arrow 61.

The casing 14 may also have a felted 60 buffer 63 in its lower end and secured to its rear wall to receive the arms 27 thereagainst when they are in lowered position. The springs 31 are adapted to maintain the arms 27 in frictional contact with the buffer 63.

65 In order to gain access to the interior of

the casing it is only necessary to unlock and raise the cover 16 and to then force the combined guard and spring member outwardly at its upper end away from the clip 29 in the back of the casing and disengage the spring 31 from the arms 27. The guard member may then be swung forwardly and downwardly upon its hinge 35. The guard member is made in one piece. The casing is made in a second piece and the cover is made in a third piece, constituting the body part of the device and in which the other elements may be easily and economically assembled.

The illustration in Figure 1 shows the 70 bars 33 fitting tightly against the arms 27 but of course any suitable spacing may be provided to permit the arms to freely operate and also to permit the outward swinging of the guard member when gaining access to the interior of the casing 14.

75 It is obvious that various changes and modifications may be made in the details of construction and design of the above specifically described embodiment of this 80 invention without departing from the spirit thereof, such changes and modifications being restricted only by the scope of the following claims.

85 What is claimed is:—

90 1. An auto signaling device comprising a casing open at one side, a plurality of indicating arms pivoted in the top of the casing and adapted to normally hang down within the casing, and a combined guard and spacing member pivotally secured to the lower end of the casing and adapted to be swung upwardly into the casing, said member having slots therein adapted to receive the indicating arms and through 95 which said arms may be operated, and a cover for the casing arranged to overhang the upper end portion of said member for holding said member in raised position 100 in the casing.

105 2. An auto signaling device comprising a casing open at one side and having a hinged cover, a guard member closing the outer side of the casing and having hinged connection at its lower end with the casing, said lower end of the guard member being offset forwardly and the upper end portion inclining upwardly and outwardly when in raised position, said cover having a depending projection at its forward end adapted to overlap said member and maintain the same in the casing, means for locking the cover in closed position, said member having slots through which said indicating arms are adapted to engage to permit free operation 115 of the arms and to maintain the same in spaced relation.

120 3. An auto signaling device comprising a casing open at one side, a plurality of indicating arms pivoted in the casing, means 125

for selectively operating the arms, a guard member pivotally mounted in the open side of the casing and adapted to be swung outwardly therefrom to permit access to the interior of the casing, a cover for the casing, means on the cover arranged to overhang the guard member when closed to maintain

it in position, and individual spring devices carried by the guard member for engagement with the indicating arms to normally urge the same into retracted position. 10

In testimony whereof I affix my signature.

GEORGE E. THIMMES.
